(57) **CLAIM**

The ornamental design for an elevator belt splice, as shown and described.

DESCRIPTION

FIG. 1 is a front perspective view of an elevator belt splice; FIG. 2 is a top view of the elevator belt splice of FIG. 1; FIG. 3 is a right side view of the elevator belt splice of FIGS. 1 and 2, the left side view being a mirror image thereof; FIG. 4 is a front view of the elevator belt splice, the rear view being a mirror image thereof; and, FIG. 5 is a bottom view of the elevator belt splice. The broken line showing in the figures is included for the purpose of illustrating environment and forms no part of the claimed design.
